United States Patent Office.

C. W. BREWER, OF RACINE, WISCONSIN.

Letters Patent No. 85,272, dated December 29, 1868.

IMPROVEMENT IN CHURNS.

The Schedule referred to in these Letters Patent and making part of the same.

To all whom it may concern:

Be it known that I, C. W. BREWER, of Racine, in the county of Racine, and in the State of Wisconsin, have invented certain new and useful Improvements in Churns; and do hereby declare that the following is a full, clear, and exact description thereof, reference being had to the accompanying drawings, and to the letters of reference marked thereon.

The nature of my invention consists in the construction of a churn in three compartments, the centre compartment containing the working-part or common dashers, whereby the cream is worked, and thrown out right and left, forming two continuous currents, in the two side compartments, and then returned in the centre or working-compartment, to be worked and thrown out as before; and, by this free rotary motion, every particle of cream is worked into butter, the butter is easily made, and easily collected.

In order to enable others skilled in the art to which my invention appertains, to make and use the same, I will now proceed to describe its construction and operation, referring to the annexed drawings, which form a part of this specification, and in which—

Figure 1 is a side elevation, in section, showing the three compartments, and

Figure 2 is a sectional elevation of another side, showing the shape of the partitions between the compartments.

A represents a circular tub, of suitable dimensions, which is provided with two T-shaped partitions, B B.

The arms of said partitions fit into grooves in the sides of the tub, and the upper edges of the partitions are below the edge of the tub, as clearly shown in fig. 2.

The tongues of the T-shaped partitions B B rest on the bottom of the tub A, leaving, on each side of them, a passage from the centre compartment C to the side compartments D D.

On the outer side of the partitions B B, that is, in the side compartments D D, are secured boards, E E, which are cut curved or circular, so that the edges thereof are even, or flush, with the edges of the tongues on the partitions B B, and the outer side corresponds with the curve of the tub.

The boards E E extend above the partitions B B, and are of the same height as the tub.

Across the tub A is placed a cylinder or shaft, F, the journals *a a* of which have their bearings, the inner one on one of the partitions B, and the other in the side of the tub, the shaft F extending across the other partition B and its board E, these latter being cut out, so that the shaft fits therein.

On the shaft F, between the partitions B B, that is, in the centre compartment C, is placed a number of dashers, G G, of any suitable form and shape.

The cover of the churn consists of a circular box, H, corresponding in size with the centre compartment C.

The sides of the box H extend downward, and fit in the grooves in the sides of the tub A, on top of the partitions B B, forming a close joint with them.

The side compartments D D are closed by lids, I I, hinged to the centre box H, as shown in fig. 1.

The shaft F, with its dashers G G, is turned by a crank, J, on the outside of the tub A.

When the cream is poured in, and the churn closed, by turning the crank J, it will be seen that the dashers G G throw the cream into the side compartments on each side, forming two continuous currents around the boards E E, the cream returning to the centre compartment, to be again thrown out.

By this arrangement, the butter is made far easier and in much less time than usual, and, when ready, it is very easy to remove the cover, dashers, and partitions, to collect the butter.

I am aware that a churn-box having screen-partitions, for forcing the cream through and around the compartments formed thereby, is not new.

What I claim, is—

The combination of the circular box A and box H with movable T-shaped partitions B B, boards E E, and shaft F, with its arms G G, all constructed, arranged, and operating substantially as herein set forth.

In testimony that I claim the foregoing, I have hereunto set my hand, this 13th day of October, 1868.

C. W. BREWER.
